CLAIM

The ornamental design for a ball weight with threaded stem, as shown and described.

DESCRIPTION

FIG. 1 is perspective view of a ball weight with threaded stem, showing my new design;

FIG. 2 is a front view of the ball weight with threaded stem shown in FIG. 1;

FIG. 3 is a left side view of the ball weight with threaded stem shown in FIG. 1;

FIG. 4 is a back view of the ball weight with threaded stem shown in FIG. 1;

FIG. 5 is a right side view of the ball weight with threaded stem shown in FIG. 1;

FIG. 6 is a top view of the ball weight with threaded stem shown in FIG. 1; and,

FIG. 7 is a bottom view of the ball weight with threaded stem shown in FIG. 1.

The broken lines in the drawings illustrate portions of the ball weight with threaded stem, that form not part of the claimed design.
